UNITED STATES PATENT OFFICE

146,733

DESIGN FOR A CONDIMENTS DISPENSER SET

Wade E. Ballard, Los Angeles, Calif., assignor to Modern Plastic Co., Los Angeles, Calif., a partnership

Application January 26, 1946, Serial No. 125,991

Term of patent 7 years

(Cl. D44—22)

To all whom it may concern:

Be it known that I, Wade E. Ballard, a citizen of the United States, residing at Los Angeles, in the county of Los Angeles, State of California, have invented a new, original, and ornamental Design for a Condiment Dispenser Set, of which the following is a specification, reference being had to the accompanying drawing, forming part thereof.

Fig. 2 is a view in side elevation of the pair of individual dispensers forming component parts of the set.

Fig. 3 is a bottom plan view of the same.

Fig. 4 is a view in end elevation of the holder for the pair of dispensers forming a component part of the set.

Fig. 5 is a bottom plan view of the same.

Fig. 6 is a top plan view of the same.

I claim:

The ornamental design for a condiment dispenser set, as shown.

WADE E. BALLARD.
